UNITED STATES PATENT OFFICE.

CYRILLE LEVEQUE, OF TORONTO, CANADA.

DESIGN FOR AN INDEX-BOOK.

SPECIFICATION forming part of Design No. 29,138, dated August 2, 1898.

Application filed May 7, 1898. Serial No. 680,069. Term of patent 7 years.

To all whom it may concern:

Be it known that I, CYRILLE LEVEQUE, a subject of the Queen of Great Britain, residing in the city of Toronto, in the county of York, in the Province of Ontario, Canada, have invented and produced a new and original Design for an Index-Book, of which the following is a specification, reference being had to the accompanying drawing, forming 10 part thereof.

The drawing is a perspective view of my index-book.

The leading feature of my design consists of an index-book having the edges of two 15 sides of the book arranged in step fashion and provided with an arc-shaped notch at the corner.

A is the main body of leaves.

B is one set of index-flaps descending from 20 one corner of the book to the corner of the same side.

It will be noticed that this set of index-flaps does not extend through the full thick-

ness of the book, but starts from a point below the top body of leaves.

25 C are the index-flaps arranged at the bottom edge of the book and extending at right angles to the flaps B. The flaps C start at a point slightly removed from the back of the book, at the upper side thereof, and extend to 30 the flaps B, the lowermost flap C being in approximately the same plane as the uppermost flap B.

D is an arc-shaped notch located at the meeting edges of the two sets of index-flaps 35 B and C and in the higher index-flaps C. The notch D extends from the top of the lowermost flap C to substantially the level of the lowermost flap B.

What I claim is—

40 The design for an index-book herein shown and described.

CYRILLE LEVEQUE.
